UNITED STATES PATENT OFFICE.

LEWIS B. DOMAN, OF ELBRIDGE, NEW YORK, ASSIGNOR TO AMPHION PIANO
PLAYER COMPANY, OF ELBRIDGE, NEW YORK, A CORPORATION OF NEW
YORK.

PNEUMATIC SELF-PLAYING MUSICAL INSTRUMENT.

No. 856,774.

Specification of Letters Patent.

Patented June 11, 1907.

Application filed October 6, 1904. Serial No. 227,471.

To all whom it may concern:

Be it known that I, LEWIS B. DOMAN, of Elbridge, in the county of Onondaga, in the State of New York, have invented new and useful Improvements in Pneumatic Self-Playing Musical Instruments, of which the following, taken in connection with the accompanying drawings, is a full, clear, and exact description.

10 This invention relates to improvements in pneumatic self-playing musical instruments, similar to that set forth in my pending application, Serial No. 221,996, filed, August 24, 1904, but involving a different mechanism 15 for controlling the expression.

In my present application, I have sought 20 to control the force of action of the key-operating pneumatics by interposing an additional pneumatic between the air exhausting device and the exhaust chambers of the pneumatic key action, and to provide this additional pneumatic with a porous valve operable manually under varying pressure or tension to control the tension of the vacuum in 25 the exhaust chambers and to thereby control the force of action of the key-operating pneumatics which are brought into communication with the exhaust chamber as the perforations in the music-sheet are registered with 30 the ducts of the tracker-board.

Other objects and uses will appear in the following description.

In the drawings Figure 1 is a detail sectional view partly in elevation of a portion of a pneumatic self-playing musical instrument 35 showing my improved expression controlling mechanism. Fig. 2 is a sectional view through the expression controlling pneumatic and its controlling lever seen in Fig. 1.

40 The keys, as —a—, of the musical instrument, are operated by striking fingers —1— which are connected by links —2— to their corresponding key pneumatics —3—. These pneumatics —3— are mounted upon suitable shelves —4— having an exhaust chamber —5— and suitable ports —6— and —7—, the ports —6— serving as a connection between the exhaust chamber —5— and pneumatic —3—, while the port —7— serves 45 to connect said pneumatic with the atmosphere. The valve —8— plays between the ports —6— and —7— to open one and close the other and is operated by a primary pneu-

55 matic —9—. Each pneumatic —3— is provided with a corresponding valve —8— and primary pneumatic —9—. These primary pneumatics are connected to the ducts of a suitable tracker-board —10— over which travels a perforated music-sheet —11—.

A partial vacuum is maintained in the exhaust chamber —5— by any suitable means, not necessary to herein illustrate or describe, but which is sufficient to cause the operation of the key-pneumatics —3— as the perforations are successively presented to the ducts 65 of the tracker-board —10—. The operation of this part of the mechanism is believed to be well understood without further description, and I will, therefore, now proceed to describe the essential feature of this invention, 70 which consists in a pneumatic —12— having separate ports —13— and —14—, the port —13— being connected by a conduit —15— to the exhaust chamber —5— and the other port —14— is adapted to be connected by a 75 conduit —16— to any suitable suction device whereby a partial vacuum may be maintained in the conduits —15— and —16— and the chamber —5—.

80 A valve —18— is mounted upon the movable wall of the pneumatic —12— to partially open or close the port 14—, said valve being provided with a felt or equivalent porous facing —19— to prevent the absolute closing of said port. The pneumatic —12— 85 is connected to and between the chamber —5— and air exhausting device, as —B—, and therefore, a partial vacuum of varying degrees of intensity is maintained in the pneumatic —12— and chamber —5— while 90 at the same time a substantially constant reserve vacuum of high tension is maintained between the pneumatic —12— and exhausting device. As the valve —18— is brought into close relation with its port —14— the 95 porous facing —19— allows the air to slowly sift therethrough sufficient to maintain a partial, but greatly subdued vacuum in the chamber —5— sufficient to cause a soft light action of the key-striking pneumatics —3—. 100 This pneumatic —12— therefore performs the function of a “governor” to regulate the musical “expression” or force of action of the key operating pneumatics and while the unretarded action of the governor in “de- 105 crescendo” or “pianissimo” effects is sub-

stantially automatic, the intermediate, or step-by-step gradations of force or expression from one extreme to the other, or the accenting of individual notes or chords is accomplished by introducing a variable or adjustable resistance which opposes with greater or less force the collapse of the pneumatic —12—. This resistance is shown as consisting of a spring —20—, having one end connected to the movable side of the bellows —12— and its other end is connected to a rock-lever —21— which is operated by a hand-lever —22—, and in turn serves to hold the lever —22— in its adjusted position.

Now, if the lever —22— is rocked into registration with the character —*pp*— of a scale —24— the tension on the spring —20— will at once be released and permit the collapse of the bellows —12— and covering of the port —14—, thereby subduing the intensity of vacuum in the chamber —5— and consequent force of action of the key pneumatics —3— to produce a pianissimo effect in the playing of a selection. If the fortissimo effect is desired, the lever —22— is rocked by hand to register with the character —*f*—, by which operation the spring —28— is tensioned to completely distend the bellows —12— and to hold it from collapse so as to maintain an unobstructed communication between the exhausting device and chamber —5— and throw the full tension of the vacuum into the key striking pneumatics. It is now seen that by adjusting the lever to points intermediate the extremes, the tension of the spring is varied and allows the valve —18— to come into more or less close relation with its port —14— which controls the intensity of the vacuum in the chamber, and therefore, a step-by-step regulation of the expression may be obtained by simply varying the tension of the spring —20— or its equivalent.

Having thus described my invention, what I claim and desire to secure by Letters Patent is—

1. In a pneumatic self-playing musical instrument, an air exhausting device, and a pneumatic connected thereto, and to atmosphere, in combination with a second pneumatic connected to and between said device and first named pneumatic a cam connected

to the second pneumatic, and a lever operating against the cam and operable manually to control the intensity of vacuum in the first named pneumatic. 55

2. In a pneumatic self-playing musical instrument, an air exhaust device, in combination with the exhaust chamber of a sound producing action communicating with said exhaust device, a pneumatic in the connection between the exhaust device and exhaust chamber of the sound producing action, a valve actuated by said pneumatic to control such communication and means including a cam and lever for controlling the operation of said pneumatic. 60

3. In a pneumatic self-playing musical instrument, an air exhausting device in combination with an exhaust chamber and a striker pneumatic connected to said chamber and to atmosphere, means including a perforated music-sheet to automatically connect the pneumatic, first with the atmosphere and then with the exhaust chamber, a second pneumatic connected to and between the exhaust chamber and said air exhaust device and having a movable member operable manually to partially close communication between said device and exhaust chamber a rocking cam connected to said movable member, and a lever operating against the cam to rock the same. 70

4. In a pneumatic self-playing musical instrument, an air exhaust device, a sound producing action having an exhaust chamber, a pneumatic having two ports, one connected to the air exhaust device, and the other connected to the exhaust chamber of the sound producing action, a valve on the movable side of said pneumatic and co-acting with the first named port to control the air tension in the exhaust chamber of the sound producing action, a lever connected to the movable side of said pneumatic and provided with an incline bearing face, and manually operated means riding upon said incline face to rock said lever. 85

In witness whereof I have hereunto set my hand this 30 day of September 1904.

LEWIS B. DOMAN.
